UNITED STATES PATENT OFFICE.

CARL M. LUTH, OF WILKINSBURG, PENNSYLVANIA.

HOPPER-CAR DOOR.

Application filed October 8, 1923. Serial No. 667,258.

To all whom it may concern:

Be it known that I, CARL M. LUTH, a citizen of the United States, and resident of Wilkinsburg, in the county of Allegheny, State of Pennsylvania, have invented certain new and useful Improvements in Hopper-Car Doors, of which the following is a specification.

This invention relates to hopper cars and while not limited thereto relates more particularly to self propelled ore transfer hopper cars, such as used to transfer ore and other materials from stock piles to bins, and the like, at steel mills and manufacturing plants.

The principal object of the present invention is to provide a novel form of closure for the hoppers of this class of cars, which will automatically form a seal when closed, thus preventing spillage, as is common with the hopper cars as heretofore used.

Another object is to provide a novel form of hopper car of the class described, having the novel design, construction and combination of parts hereinafter described and illustrated in the accompanying drawings.

Heretofore hopper cars have been formed with their hinged sides or doors adapted to close, forming a butt joint and if, as is often the case, any of the material being hauled would adhere at points along the lower edge of the doors, the doors would not close tightly together, but remain spaced sufficiently to permit spillage along the whole path of travel. Also with the doors formed as heretofore, when the load was put in the car they would spring slightly open, even if they were tightly closed, before the load was deposited, thus permitting spillage.

All of these disadvantages are overcome with cars constructed in accordance with this invention, and spillage is prevented.

In the drawings, Figure 1 is a top plan of a car constructed in accordance with this invention.

Figure 2 is a side elevation thereof.

Figure 3 is an enlarged cross sectional elevation on the line III—III of Figure 2.

Referring more particularly to the drawings, the numeral 2 designates the wheeled trucks of the car supporting the sill portion 3, upon which is secured the side walls 4 and 5, end walls 6 and 7 and front and rear cabs 8 and 9.

The car is divided intermediate its ends

by a transverse wall or partition 10 into two longitudinally extending hopper portions A and B. The side walls 4 and 5 and end walls 6 and 7 and walls of partition 10 are inclined inwardly and downwardly to facilitate the movement of the material carried by the car through the hoppers.

The hopper portions A and B each have their bottom adapted to be closed by inclined doors 12 and 14 hinged along their upper edge to the sides of the car body.

The door 12 of each hopper is provided with a longitudinally extending groove 15 adjacent its lower edge, which groove is provided with beveled or outwardly flaring side walls and a flat bottom, and the door 14 of each hopper is provided with a longitudinally extending lip or projection 16 having its lower edge beveled to correspond with the lower inclined or beveled side face of the V-shaped groove 15 in the door 12. The lip 16 of the door 14 is adapted to enter and form a sealing connection or joint with the groove 15 of the door 12 when said doors are closed. The lower sides of the groove 15 and the lip 16 being substantially parallel.

It will be readily seen that with doors constructed in accordance with this invention they may spring a limited amount, due to the depositing of the load without opening a passage through which the loaded material will spill, and, further, if particles of the material should stick onto the doors when being discharged, such material, due to the novel form of the groove 15 and lip 16 and the position they assume upon closing, will be pushed upwardly into the hopper and not interfere with the complete closing of the doors.

While only one specific embodiment of the invention has been illustrated and described, it will be understood that various modifications may readily be made without departing from the scope of the invention as defined in the appended claims.

I claim:

1. A hopper car having the hoppers extending longitudinally thereof, and the bottom of said hoppers being closed by inclined hinged doors, one of said doors being provided with a longitudinally extending groove on its inner face adjacent its lower edge, said groove having beveled side walls and a flat bottom face, and the other of said doors being provided with a projecting lip

along its lower edge, said lip being provided with a beveled lower edge and being adapted to project into said groove when said doors are in closed position to form a sealed joint.

2. A self propelled ore transfer hopper car having a plurality of longitudinally extending hoppers, each of said hoppers having their bottom closed by inclined hinged doors, said doors being hinged along their upper edges to the body of said car, one of said doors being provided with a longitudinally extending groove on its inner face adjacent its lower edge, said groove having outwardly flaring side walls, and the other of said doors being provided with a projecting lip along its lower edge, said lip being provided with a beveled lower edge and being adapted to project into said groove, so that said beveled lower edge of said lip will

form a sealing connection with the lower side wall of said groove.

3. A hopper car having a plurality of hoppers, each of said hoppers having their bottom closed by inclined hinged doors, said doors being hinged along their upper edges to the body of said car, one of said doors being provided with a longitudinally extending groove on its inner face adjacent its lower edge, said groove having beveled side walls and a flat bottom face, and the other of said doors being provided with a projecting lip along its lower edge, said lip being provided with a beveled lower edge and being adapted to project into said groove when said doors are in closed position to form a sealed joint.

In testimony whereof I have hereunto signed my name.

CARL M. LUTH.
